W. J. DRUCKER

RADIATOR FOR INTERNAL COMBUSTION ENGINES

Filed Oct. 23, 1922

UNITED STATES PATENT OFFICE.

WILLIAM JOSEPH DRUCKER, OF PITTSBURGH, PENNSYLVANIA.

RADIATOR FOR INTERNAL-COMBUSTION ENGINES.

Application filed October 23, 1922. Serial No. 596,512.

To all whom it may concern:

Be it known that I, WILLIAM J. DRUCKER, a citizen of the United States, and a resident of Pittsburgh, in the county of Allegheny and State of Pennsylvania, have invented 5 certain new and useful Improvements in Radiators for Internal-Combustion Engines, of which the following is a specification.

This invention relates to radiators for internal combustion engines.

The present invention is adapted for use in connection with radiators of the water cooled type employed for internal combustion engines on motor vehicles, or the like.

15 The object of the invention is to provide an attachment for radiators of the above character whereby cool air may be circulated within the same to carry off heat collected by the cooling medium within the 20 radiator.

A further and important object of the invention is that the device may be attached to the filling neck or nipple of the radiator.

A still further object of the invention is 25 that the device be adapted to indicate to the driver of the motor vehicle when the water or cooling medium within the radiator to which the same may be attached reaches a high temperature.

30 Other objects, and objects relating to details of construction, combination and arrangement of parts will hereinafter appear in the detailed description to follow.

The invention is illustrated by way of example in the accompanying drawings, in 35 which:—

Figure 1 is a perspective view showing a front portion of the motor vehicle and the invention applied.

40 Figure 2 is a vertical sectional view of the device when applied and taken at right angles to the longitudinal axis of the radiator to which the same is applied.

Figure 3 is a perspective view of the signal valve employed in connection with the present device.

Referring to the drawings more particularly, 10 indicates generally a radiator casting and 11 the core therefor. At 12 is shown 50 the filler neck or nipple which terminates at its upper end in an annular enlargement 13 interiorly threaded and adapted to receive the usual cap for closing the same. The

present radiator is of the type and construction which may be filled with water or a 55 similar cooling medium and this water circulates about the water jackets of the associated engine for cooling the engine cylinders. At 14, Figure 2, there is shown the usual over-flow pipe which projects upwardly within the filler neck or nipple 12.

In carrying out the present invention there is provided a short tubular body member or nipple 15 which is provided with 60 threads 16 upon its lower end adapted to be threaded in the upper end of the filler neck 12, as shown to advantage in Figure 2. The nipple or tubular body member 15 is slightly 65 greater in diameter than the neck 12 and terminates at its upper end in a closure 16 which is preferably curved, as shown, and the said closure in turn continuing into a bell-shaped lateral extension 17, the interior 70 of which communicates with the interior of the body member 15 through the passage 18. In the passage 18 there is preferably positioned a screen 19 whereby to eliminate any 75 passage of particles into the tubular member or nipple 15.

The interior of the body member 15 at its 80 upper end is formed with an annular flange 20, the upper surface of which preferably slopes, as shown, and said flange provides a restricted passage or entrance into the member 15.

A valve member V is provided which 85 preferably consists in an annular casting 22 having a bottom closure 23 and a top closure 24 which is conical in shape and terminating at its upper end in a threaded nipple 25. 90 The casting 22 is hollow thus forming the two walls 26 and 27, and between these two walls there is formed a plurality of passages 28 which are arranged in circular formation and adapted to establish communication between the interior of the filler neck or 95 nipple 12 and the passage 21 when said valve member is in a position illustrated in Figure 3.

100 Into the nipple 25 there is threaded the lower end of a rod 29, said rod extending through an aligned opening 30 in the closure 16 and terminating in a ball 31. The ball 31 may be made of any material desired in order to suitably weight the valve V.

105 In the operation of the present device, as-

suming that the same is attached to a motor vehicle, in the manner heretofore described, with the forward movement of the motor vehicle air will pass through the valve-shaped member 17 into the passage 18, and from thence through the passage 21, and downwardly through the passages 28 and into the upper end of the radiator casing 10. As indicated in Figure 2 the radiator is slightly less than filled with water or other cooling medium employed thus leaving a space in the upper end of the radiator into which the air may pass. As indicated by arrows in Figure 2, the cooled air entering the filling neck or nipple 12 will circulate about and above the water within the radiator and move upwardly and pass out through the over-flow pipe 14.

Should the water or other cooling medium within the radiator reach a high temperature and expand to such a degree that the same would raise the valve member V to the dotted line position shown in Figure 2, then air will not be permitted to enter the radiator. Upon the valve member reaching this position, the ball 31 will be raised to the dotted line position shown, and this ball will then indicate to the driver that his engine is heated to a relatively high degree and that he should guard against over heating the same in the further operation thereof. The ball 31 therefore is only brought to a signalling position when the engine has reached a relatively high degree of temperature.

While I have shown and described the preferred form of my invention, I wish it to be understood that I am aware of the fact, that the construction, combination and arrangement of parts may be changed by those skilled in the art, without departing from the spirit of the invention as indicated by the appended claims.

I claim:

1. An attachment of the character described, comprising a nipple terminating at its one end in a laterally extending bell-shaped member, a valve member within the nipple adapted to permit free passage of air in either direction and adapted to move upward upon a predetermined amount of liquid pressure therebeneath and close the passage through said nipple, and a visible signal element carried by said valve member and exposed exteriorly of said nipple.

2. An attachment of the character described, comprising a nipple terminating at its one end in a laterally extending bell-shaped member communicating with the passage through the nipple, a valve member within the nipple adapted to permit free passage of air in either direction and adapted to move upward upon a predetermined amount of liquid pressure therebeneath and close the passage through said nipple, a visible signal element carried by said valve

member and exposed exteriorly of said nipple, and a reticulated closure in the passage establishing communication between the interior of the nipple and said bell-shaped extension.

3. In combination with a radiator filling neck terminating at its free end in an enlargement interiorly threaded and forming a shoulder with the associated end of the neck, a nipple having its one end threaded and adapted to be connected to the enlarged interiorly threaded end of the neck, an annular baffle member carried upon the inner periphery of said nipple, a valve member fitted within said nipple and disposed between said neck and baffle member, said valve member being adapted to seat upon the shoulder of said neck and having openings adapted to permit the passage of air therethrough and into said neck, and said openings being arranged whereby when the valve is lifted against said baffle the same are closed, for the purpose described.

4. An attachment of the character described comprising a nipple having its one end threaded and adapted to be connected with the filler neck of a radiator and its other end terminating in a laterally extending and outwardly flared portion, an annular baffle member formed upon the inner wall of said nipple, a valve member seated within the nipple, and beneath said baffle member, said valve member having openings whereby when the same is disposed in spaced relation beneath the baffle member air may pass through said nipple and into said neck and when the same is lifted against the baffle member the passage through said neck is closed.

5. An attachment of the character described comprising a nipple having its one end adapted to be fitted upon the filler neck of a radiator and its other end terminating in a laterally extending and outwardly flared portion, an annular baffle member formed upon the inner wall of said nipple, a valve member seated within the nipple and beneath said baffle member, said valve member having openings adjacent its periphery whereby when the same is disposed beneath said baffle member air may freely pass through said nipple and into the filler neck and when the baffle member is raised to engage beneath the baffle member said openings become closed and thereby to close the passage through said nipple.

6. An attachment of the character described comprising a nipple having its one end adapted to be fitted upon the filler neck of a radiator and its other end terminating in a laterally extending and outwardly flared portion, an annular baffle member formed upon the inner wall of said nipple, a valve member seated within the nipple and beneath said baffle member, said valve member

having openings adjacent its periphery sage through said nipple, and a guide rod whereby when the same is disposed beneath extending upwardly from said valve member said baffle member air may freely pass and through the wall of the nipple, where-¹⁰ through said nipple and into the filler neck by to facilitate the movement of said valve member.
5 and when the baffle member is raised to en-
gage beneath the baffle member said open-
ings become closed thereby closing the pas-

WILLIAM JOSEPH DRUCKER.
